FEEDING AND MEASURING MACHINE FOR SHEET MATERIAL

Herman L. Seiden, Chicago, Ill., assignor to Lectromatic
Devices, Inc., Chicago, Ill., a corporation of Illinois

Filed May 15, 1958, Ser. No. 50,902

Term of patent 14 years

(Cl. D55—1)

FIG. 1

FIG. 2

Fig. 1 is a front perspective view of a feeding and measuring machine for sheet material embodying my new design, the end of the machine not seen being identical to that shown;

Fig. 2 is a rear elevation of the same.

The dominant features of the design reside in the portion shown in full lines.

I claim:

The ornamental design for a feeding and measuring machine for sheet material, as shown and described.
